CLAIM

The ornamental design for an oral-motor therapy tool, substantially as shown and described.

DESCRIPTION

FIG. 1 is a top, front, left perspective view of a first embodiment of an oral-motor therapy tool, showing our new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a top, front, left perspective view of a second embodiment of the oral-motor therapy tool;

FIG. 9 is a left side elevation view thereof;

FIG. 10 is a right side elevation view thereof;

FIG. 11 is a rear elevation view thereof;

FIG. 12 is a front elevation view thereof;

FIG. 13 is a top plan view thereof; and,

FIG. 14 is a bottom plan view thereof.

The areas inside the dashed lines in FIGS. 1-3, 6-10, and 13-14 form no part of the claimed design.
